UNITED STATES PATENT OFFICE.

AUSTIN F. JACKSON, OF TAUNTON, MASSACHUSETTS.

DESIGN FOR A TEAPOT.

SPECIFICATION forming part of Design No. 32,058, dated January 2, 1900.

Application filed December 5, 1898. Serial No. 698,377. Term of patent 14 years.

To all whom it may concern:

Be it known that I, AUSTIN F. JACKSON, a citizen of the United States, residing at Taunton, in the county of Bristol and State of Massachusetts, have invented and produced a new and original Design for Teapots, of which the following is a specification, reference being had to the accompanying drawings, forming part thereof, in which—

Figure 1 is a side view of a teapot, showing my new design. Fig. 2 is a cross-section on about line A B, Fig. 1. Fig. 3 is a cross-section on about line C D, Fig. 1. Fig. 4 is a cross-section on about line E F, Fig. 1. Fig. 5 is a cross-section on about line G H, Fig. 1; and Fig. 6 is a plan view of the body of the teapot.

As shown in the drawings, the leading or material feature of my design consists in the raised ornamental work applied on cover and neck in the form of a foliated flowered spray.

Minor features of my design consist in the ornamentation of the handle, the spout, and the feet.

The spray 1 on the cover has the daisy-like flower 2 and partakes of the general design of the sprays 3 upon the neck of the teapot, such sprays 3 being symmetrically disposed on opposite sides of a central line and having

the depending branches and the horizontally disposed branches leading laterally outward from the upper end of their respective depending branches, such branches having the daisy-like flowers, as shown.

The spout 4 has the scroll ornament 5 on its upper side at its outer end, the scroll ornaments 6 and 7 on, respectively, its upper and lower sides at its inner end, and the scroll ornament 8 upon its sides near its inner end.

The handle 9 has at the juncture of its upper end with the body of the teapot the ornamentation 10, simulating wrinkled folds, and is provided with scroll ornaments 11 at its lower end and with a composite scroll and floral ornamentation 12 at its upper end.

The legs 13 are ornamented by the scrolls 14 of the Corinthian order.

Having described my invention, what I claim as new, and desire to secure by Letters Patent, is—

The design for a teapot, as herein shown and described.

AUSTIN F. JACKSON.
